(57) **CLAIM**

The ornamental design for a gate antenna, as shown and described.

DESCRIPTION

FIG. 1 is a top, front, and right side perspective view of the first embodiment of a gate antenna showing the new design; FIG. 2 is a front view thereof;

FIG. 3 is a rear view thereof;

FIG. 4 is a left side thereof;

FIG. 5 is a right side view thereof;

FIG. 6 is a bottom, rear, and left side perspective view thereof;

FIG. 7 is a top, front, and right side perspective view of the second embodiment of a gate antenna, showing the new design;

FIG. 8 is a front view thereof;

FIG. 9 is a rear view thereof;

FIG. 10 is a left side view thereof;

FIG. 11 is a right side view thereof; and,

FIG. 12 is a bottom, rear, and left side perspective view thereof.

The broken lines shown in the figures illustrate portions of the article and form no part of the claimed design.

The top views and bottom views of the first and second embodiments are omitted since they do not contain ornamental features.

1 Claim, 12 Drawing Sheets
